(No Model.)

R. LAUCKNER.

BOILER FEEDER.

No. 281,380.

Patented July 17, 1883.

Inventor:

Richard Lauckner

by his Atty M. J. Sprague

UNITED STATES PATENT OFFICE.

RICHARD LAUCKNER, OF BAY CITY, ASSIGNOR OF ONE-HALF TO SOPHIA JOCKEN, OF EAST SAGINAW, MICHIGAN.

BOILER-FEEDER.

SPECIFICATION forming part of Letters Patent No. 281,380, dated July 17, 1883.

Application filed January 31, 1883. (No model.)

To all whom it may concern:

Be it known that I, RICHARD LAUCKNER, of Bay City, in the county of Bay and State of Michigan, have invented new and useful Improvements in Boiler-Feeders; and I hereby declare that the following is a full, clear, and exact description thereof, reference being had to the accompanying drawings, which form a part of this specification.

10 The object of my invention is to construct a mechanical boiler-feeder, which, although working on a known principle of feeding, shall have such constructive merits as to render the device strictly reliable, and so simple that, 15 should it get out of order, it can, from its very simplicity in construction and manner of operation, be easily repaired by any ordinarily-skilled mechanic; and my invention therefore consists in the arrangement and combination of its various parts, all as more fully hereinafter set forth.

Figure 1 is a vertical central section of the device, showing all its different connections with the boiler and the source of water-supply. Fig. 2 is a top plan of one of the two-like valve-seats. Fig. 3 is a plan of one of the valve-faces.

In the accompanying drawings, A A are two rotary valve-disks attached to a common stem, 30 B, bearing on the top the bevel crown-gear C, which meshes with another bevel-gear, D, and through which continuous rotary motions can be communicated to the valves A A. Each of the valves A is provided, first, with a port, 35 a, which leads from the face of the valve to the opposite side thereof, and the ports b c, which communicate, through a duct, d, in the body of the valve, with each other.

Interposed between the valves A A is a short 40 cylinder, E, of larger diameter than the valves, its top and bottom having central funnel-shaped depressions corresponding with the concavo-conoidal valve-faces, which are seated thereon steam and water tight. The cylinder 45 E is provided with the inlet-coupling F, the outlet G, diametrically opposite thereto, a duct, f, connecting the port g with the outlet G, and duct h, connecting the port i with the inlet F, and a large annular water space or passage, H, 50 connecting with the two ports k and l. The

annular water space or passage H occupies the whole interior of the cylinder E, but is entirely separated from the ducts f and h by partition-walls. With the parts in position as shown in Fig. 1, the ports g i correspond 55 with the ports b, and the ports l and k with the ports c.

I and I' are two dome-shaped castings, each provided with a pipe-coupling, m, and annular flanges n, the latter ones forming the means 60 for fitting these domes steam-tight, one to the top and the other to the bottom side of the cylinder E. The top dome, I', is provided with a stuffing-box, o, through which the valve-stem B passes; and p is a spring by means of which 65 the valves A are firmly held to their seats, even after considerable wear.

K is a pipe connecting the steam-space of the boiler with the top of the device, and L is another pipe connecting the boiler, below the 70 water-line, with the bottom of the device.

M is the water-supply pipe conducting water, under the ordinary pressure received from an elevated tank or from water-mains, to the device. When in proper position, the vertical center of the device should be about on the 75 same level with the ordinary height of water in the boiler.

In practice the valves A are continuously revolved by means of the connections described, 80 power being applied to a pulley, N, which rotates the bevel-gear wheel D. With the valves in the position shown in Fig. 1, water is admitted through the pipe M into the duct h. From thence it flows through the port i into 85 the port b of the lower valve, then through ducts d, ports c, and the ports k into the water-space H, filling the same up until it overflows through ports l and c, duct d, and port b of the upper valve into the duct f, and from thence 90 into the waste-pipe G; but as the valves A are continually revolving, all intercommunication between the valve and water-space H will soon be cut off completely, and retain the water which has filled into the space H until the port 95 a of the upper valve becomes coincident with the port l, the position of the valves A being exactly the reverse of that shown in Fig. 1, and corresponding to one-half a revolution. Now, 100 the steam from the boiler, which is free to en-

ter the dome I', finds access to the space H through the coinciding ports *a l*, and as the corresponding ports, *a* and *l*, are also coincident with each other, the water confined in the space H is free to flow into the lower dome, from whence all or a certain quantity of it will pass to the boiler, according to the difference in pressure in the boiler and in the feeder. As the valves are continually rotating, the feeding process will go on continuously, and if the relative size of the feeder is properly calculated and the speed with which the device feeds is properly adjusted, it is clear that the level of water in the boiler can be maintained as long as the device is in working order. No overfeeding can occur if the device is properly adjusted as to its vertical height, as the water in the boiler cannot obtain a level above that in the cylinder E. If too much overflow occurs at G, the supply of water through the pipe M may be reduced. The particular contracted funnel shape of the valve faces and seats insures an even wear of the same, and I have made this feature the subject of another application.

What I claim as my invention is—

1. The cylinder E and shell I I', in combi-

nation with the two continually-rotating twin valves A and a series of intercommunicating ports, whereby alternate communication is made and broken between the water-space in the cylinder, water supply and overflow, and between said water-space, steam-space, and the water-space in the boiler, whereby, first, a quantity of feed-water is admitted to the water-space, and then conveyed by gravity into the boiler, substantially as described. 30

2. In a boiler-feeder acting by gravity-pressure, the combination of the rotary twin valves A A, ported as described, stem B, and devices 40 for giving the same a continuous rotary motion, substantially as and for the purpose set forth.

3. In a mechanical boiler-feeder, the water-cylinder E and valves A A, in combination 45 with the ports *k l*, *a a*, *b b*, *c c*, and ducts *d f*, and *h*, when constructed, arranged, and operating substantially as and for the purpose specified.
